UNITED STATES PATENT OFFICE.

THOMAS CHENEY LAWLESS, OF GARDEN CITY, LOUISIANA.

BRACKET.

1,116,597.

Specification of Letters Patent.

Patented Nov. 10, 1914.

Application filed June 3, 1914. Serial No. 842,745.

To all whom it may concern:

Be it known that I, THOMAS CHENEY LAWLESS, a citizen of the United States, residing at Garden City, in the parish of St. Mary and State of Louisiana, have invented a new and useful Bracket, of which the following is a specification.

The device forming the subject matter of this application is a bracket of that general 10 type which is employed for supporting a cableway or track in connection with logging and other operations.

The invention aims primarily to provide 15 novel means for holding the bracket in place upon a support.

It is within the scope of the invention to improve generally and to enhance the utility of devices of that type to which the present invention appertains.

20 With the above and other objects in view which will appear as the description proceeds, the invention resides in the combination and arrangement of parts and in the details of construction hereinafter described 25 and claimed, it being understood that changes in the precise embodiment of the invention herein disclosed can be made within the scope of what is claimed without departing from the spirit of the invention.

30 In the accompanying drawing:—Figure 1 shows the invention in perspective, applied and in use; Fig. 2 is a side elevation of the bracket and attendant parts, portions being broken away; Fig. 3 is a cross sectional view 35 depicting the bracket and attendant parts in top plan; Fig. 4 is a vertical section of the outer end of the bracket; Fig. 5 is a cross section on the line 5—5 of Fig. 4; Fig. 6 is a perspective detail illustrating one end of 40 the bracket.

In carrying out the present invention there is provided a bracket denoted generally by the numeral 1, the bracket 1 including a lower leg 2 provided with an upright 45 foot 3 having an inwardly extended toe 4. Adjacent its upper end the leg 2 of the bracket is provided with an inwardly extended flange 5, the upper end of the leg 2 terminating in an upright clamp 6.

50 The upper leg 7 of the bracket is disposed in diverging relation to the lower leg 2 and includes an upright foot 8 alined with the foot 3, the foot 8 terminating in an inwardly projecting toe 9 disposed approximately parallel to the toe 4. As shown best in Fig. 4, the leg 7 includes an extension 10 disposed

parallel to the outer portion of the leg 2 and fitting thereagainst, the extension 10 terminating in an upright clamp 11, coöperating with the clamp 6, the clamps 11 and 6 being recessed upon their inner faces as shown at 12 to receive and hold a track 14, which preferably takes the form of a cable. By means of screws 15 and 16, the outer ends of the legs 2 and 7 of the bracket are held together, so that the clamps 11 and 6 coöperate to grip the track 14.

The numeral 17 indicates a support which may be a tree or stump and in the support 17 recesses 18 are formed to receive the toes 70 9 and 4, the feet 8 and 3 resting against the outer face of the support. A flexible element which may be a chain 19 is passed around the stump or support 17 and is extended across the foot 3 of the bracket, the 75 end 20 of the chain 19 being engaged in the reduced throat of a gripping link 21 on the other end of the chain. By the operation above described, the lower leg of the bracket is bound securely against the stump or support 80 17. A flexible element 22 is passed around the support 17 and around the foot 8 of the bracket. At this point it may be noted, as indicated at 36, that the feet of the brackets are notched in their edges, as 85 shown in Fig. 6, to receive the chain 19 and the flexible element 22, for the obvious purpose of holding them in place. One end of the flexible element 22 carries a swivel eye 23 through which the flexible element is 90 passed. The extremity of the flexible element, beyond the swivel eye 23 is prolonged to form a guy which is secured as indicated at 25 in any desired manner to a support such as a stump or tree 26.

95 Intersecting braces 27 are pivoted as shown at 28 to the flange 5 and pivoted to the ends of the braces 27 are driving dogs 29 which in general outline resemble the hook of a peavey, the dogs 29 being adapted 100 to be driven into the stump or support 17.

A guy in the form of a flexible element 30 is attached to the flange 5 and is extended laterally in the general direction of the length of the track 14. The guide 30 is connected by means of a turnbuckle or the like 31 with a chain or the like 32 passed around a stump or other support 33, the free end 34 of the chain 32 being engaged in the retracted throat of a gripping link 35 at one 110 end of the chain.

In practical operation, the legs 2 and 7

of the bracket are loosely connected by means of the screws 16 and 17, the lower leg of the bracket being held in place through the medium of the chain 19 and the dogs 29 being driven into the stump or support 27. The cable or track 17 is then engaged in the recesses 12 of the clamps 6-11 and after the cable or track has been stretched out tightly, the clamps are tightened up on the cable 10 through the medium of the screws 15 and 16. The loop 24 in the flexible element is formed and is assembled with the support 17 and the upper end of the leg 7, and the end of the flexible element 22 is connected with the 15 stump or other support 26. The loop 24 and the guy portion of the flexible element 22 exercise two functions. First they serve to hold the upper end of the bracket in place, and second, they act as a guy tending to prevent the support 17 from yielding or swinging. Under ordinary working conditions, the load always travels along the track 14 in the direction of the arrow A. It is to 20 prevent the lateral swinging of the bracket 25 1 and consequent loosening or slackening of the track 14 that the laterally extended flexible element or guy 30 is provided, it being obvious that the guy in question may be tightened up to any desired extent through 30 the medium of the turn buckle 31.

Through the instrumentality of the simple structure hereinbefore described, the track or cable way may be prolonged an almost indefinite length through the forest, thereby 35 permitting the logging operations to be carried on at a considerable distance from the saw mill, donkey engine or other source of power.

Having thus described the invention, what 40 is claimed is:

1. In a device of the class described, a support; a bracket bearing at its upper and lower ends against the support; means for attaching one end of the bracket to the support; a slip-noose passed around the other end of the bracket and the support, the slip-noose including a laterally extended end; and means for securing the laterally extended end at a distance from the support to 50 render the laterally extended end effective as a guy for the support, and to tighten the noose about the bracket and the support.

2. In a device of the class described, a bracket provided with diverging legs having 55 alined, support-engaging feet, the feet being

provided with approximately parallel toes disposed at angles to the respective feet; and support-engaging binders passed transversely of the feet.

3. In a device of the class described, a bracket comprising diverging, support-engaging legs; intersecting braces pivoted to the bracket and located between the legs; and support engaging dogs pivoted to the braces; the braces and the dogs being movable transversely of the legs.

4. In a device of the class described, a bracket; support engaging means carried by the ends of the bracket; a track supported on the bracket; a guy connected to the bracket adjacent its track receiving portion, the guy being extended to one side of the bracket in the general direction of extent of the track; and means for securing the guy; the guy constituting means for preventing a lateral swinging of the bracket when a load traverses the track.

5. In a device of the class described, a bracket comprising diverging legs, the legs being provided with superposed nested angular portions; a securing device connecting the nested angular portions of the legs; the angular portions of the legs being mutually recessed at their extremities and being held together by the securing device to form a track receiving socket.

6. In a device of the class described, a bracket comprising diverging legs, one of which is provided with a flange and with a clamp disposed at an angle to the flange, the other of which legs rests on the flange and includes a clamp co-operating with the clamp of the first specified leg; means for holding the legs together to cause the clamps to co-operate; and support engaging means assembled with the flange.

7. In a device of the class described, a bracket comprising diverging legs and provided with a flange located between the legs; support engaging dogs; means for pivotally connecting the dogs with the flange; and a laterally extended guy connected with the flange.

In testimony that I claim the foregoing as my own, I have hereto affixed my signature in the presence of two witnesses.

THOMAS CHENEY LAWLESS.
